CLAIM

The ornamental design for an upper edge for a front wall of a shopping cart basket, as shown and described.

DESCRIPTION

FIG. 1 is a perspective view of an upper edge for a front wall of a shopping cart basket, showing my new design;

FIG. 2 is a top plan view thereof;

FIG. 3 is a front elevational view thereof;

FIG. 4 is a sectional view thereof, as taken along line 4—4 of FIG. 3, in a direction indicated by arrows; and,

FIG. 5 is a sectional view thereof, as taken along line 5—5 of FIG. 3, in a direction indicated by arrows.

A sectional view thereof would be a mirror image of FIG. 4, if taken along line 4—4 of FIG. 3, in a direction opposite to the direction indicated by arrows in FIG. 4.

Broken line illustrations of other portions of a shopping cart basket and broken line illustrations of other elements of a shopping cart are not parts of the design claimed.
